Filed Apr. 16, 1970, Ser. No. 22,474

Term of patent 14 years

Int. Cl. D24—03

U.S. Cl. D24—1

FIG. 3

FIG. 2

FIG. 1 is a perspective view of a machine for centrifugally casting dental materials showing my new design; FIG. 2 is a front elevational view thereof;

FIG. 3 is a side elevational view thereof, as seen from the left in FIG. 2;

FIG. 4 is a rear elevational view thereof;

FIG. 5 is a top plan view thereof; and

FIG. 6 is a side elevational view thereof taken substantially in the direction of arrows 6-6 in FIG. 5.

The broken-line showing of a supporting surface is merely for illustrative purposes.

I claim:

The ornamental design for a machine for centrifugally casting dental materials, substantially as shown and described.
